UNITED STATES PATENT OFFICE.

KARL EMIL LEONARD LIEDSTRAND, OF STOCKHOLM, SWEDEN.

CARDS ADAPTED FOR STATISTIC OR SIMILAR PURPOSES AND APPARATUS FOR SORTING THE CARDS.

1,261,413.

Specification of Letters Patent.

Patented Apr. 2, 1918.

Application filed August 23, 1916. Serial No. 116,566.

To all whom it may concern:

Be it known that I, KARL EMIL LEONARD LIEDSTRAND, a subject of the King of Sweden, and resident of Vollmar-Yxkullsgatan 5, Stockholm, in the Kingdom of Sweden, have invented certain new and useful Improvements in Cards Adapted for Statistic or Similar Purposes and Apparatus for Sorting the Cards, of which the following is a 10 specification, reference being had therein to the accompanying drawings.

In the statistic treating of data card systems are used to a large extent. A card is prepared for each "individual" (unit) of 15 the statistical collection, which card then represents the said individual. The said card is provided with notes or other marks, indicating the groups, to which the individual belongs according to certain grounds of 20 classification. When the statistic primary matter has been transformed into the shape of cards, the cards are sorted into groups in accordance with the said notes or marks. The number of cards of each group are then 25 counted or certain numeral statements on the cards of each group are summed. The numbers or sums thus obtained form together a statistic table, forming the first result of the treating of the statistic matter. 30 In order to facilitate and shorten the time-consuming work, necessary for making the said notes or marks, for the sorting operation and the counting of the cards, one has to a large extent passed from making notes 35 on the cards to providing the cards, on different parts of the same, with slots of such character, that the sorting and summing of the cards can be effected by an apparatus instead of manually. 40 This invention relates to cards provided with means and slots of a special system, which render possible a rapid and simple sorting operation. The invention also relates to a sorting apparatus adapted to cards 45 arranged in accordance with this invention.

In order that the invention and the applying of the same may be more easily comprehended, a short statement of the said system of slots and the sorting operation 50 effected by means of the same in the apparatus is first given.

On each card a section is reserved for each ground of classification, for instance age, confession of faith, civil status and so on. 55 Each of the said sections of the card is pro-

vided with a slot extending from a certain point and in a certain direction, the slots of the corresponding sections of the cards having different length, so that a slot of a certain length provided in a certain section 60 designates a certain group of the classification corresponding to the section. If, for instance, the section of the card is reserved for confessions of faith, a slot of a certain length provided in the said section of one 65 card may correspond to the Lutheran confession, while the slot of a different length provided in the same section of another card corresponds to the Catholic confession and so on. By means of the said slots and a 70 bar or the like, on which the cards are mounted with the slots straddling the said bar, the cards are held at different levels. Owing to the said arrangements all cards belonging to the same group of the classification in question are held at the same level, 75 which differs from the levels of the rest of the cards.

The apparatus adapted for the sorting of the cards consists of a frame, into which a 80 bar or the like may be mounted in different positions, corresponding to the different points from which the slots extend, the said frame and bar being so arranged that the 85 cards, straddling the bar by means of the slots having the same position, descend to different levels determined by the lengths of the slots. For rendering possible an easy removal of the cards by groups from the collection, the cards, according to this invention, are provided with arrangements partly for the withdrawing of the cards 90 from the collection partly for the locking of all of the remaining groups. The arrangement for the withdrawing of the cards 95 may consist of holes provided in the cards and so located, that a fork for instance may be threaded into the holes of the cards, which belong to the same group and consequently are on the same level, the highest 100 level for each occasion. The arrangement for locking the cards, so that, as a group of cards is being withdrawn, no cards of the other groups will accompany the same, consists of notches, holes or the like, which can 105 be engaged by ribs, needles or the like provided in the sorting apparatus.

In the accompanying drawings Figure 1 is a side view and Fig. 2 a plan view of a form of the sorting apparatus, shown as an 110

example. Figs. 3 and 4 show in a sectional view and in a side view respectively a device provided in the sorting apparatus for causing the cards, mounted in the apparatus, to be brought into positions, in which their end edges are flush with one another. Figs. 5 and 6 show, viewed from two different sides, a device for locking the cards by groups in the sorting apparatus. Fig. 7 shows the bar mentioned above and cards straddling the same. Fig. 8 shows on a reduced scale a card arranged in accordance with this invention. Fig. 9 shows the same card provided with slots adapted for the sorting system mentioned above. Figs. 10 and 11 show parts of cards with modified arrangements for the locking of the cards by groups. Fig. 12 shows a part of a card provided with slots for the sorting of the cards, said slots extending from a certain level into the cards. Fig. 13 shows a modification of the cards. Fig. 14 shows a modified form of the device for adjusting the cards, mounted in the sorting apparatus.

25 The card, shown in Fig. 8 as an example, is rectangular, which shape is the most suitable. The said card is provided with two holes *a*, located near its top edge, at a suitable distance from the same, into which the 30 fork, mentioned above, is threaded for the withdrawing of the cards from a collection. One of the end edges of the card is provided with notches or recesses *b*, adapted to be engaged by ribs, provided in the sorting apparatus, for the locking of the cards, as 35 stated more particularly below. In the shown card sections are indicated adapted to be cut out. The card is adapted for popular statistics and for that purpose the card 40 has sections 1, 2... for age, confession of faith, civil status and so on. The said sections extend from one of the longitudinal edges of the card or from its lower edge, as shown, and are parallel to the end edges 45 of the card. If the card is adapted for any other statistic purpose, it is provided with sections adapted therefor.

As the cards are to be used, they are provided, for instance in the statistic office, 50 with slots in the following manner. If, as already stated, the section designated with 3, is adapted for confession of faith, a slot *c*, Fig. 9, is made in a card, which shall represent for instance a Lutheran, which slot 55 extends from the lower edge of the card upward longitudinally of the section to a level, for instance to the horizontal row designated with 4, which, consequently, corresponds to the Lutheran confession. In an 60 other card, representing a person of another confession of faith, for instance the Catholic confession, the slot provided in the vertical section 3 extends to a different horizontal row, which, consequently, corresponds to the Catholic confession of faith.

65

If the vertical section designated with 4 is adapted for the civil status (unmarried, married, widower and so on), the slot *d* made in the said section of a card (representing an unmarried person) extends for 70 instance up to the horizontal row designated with 0, which, consequently, is adapted for unmarried persons, while the slot made in another card (representing a married person) extends to another horizontal row, 75 adapted for married persons. The slots are arranged in the same manner in the other vertical sections, corresponding to other personal data respectively. The slots in the illustration shown in Fig. 9, end in a circular opening *e*. However, the openings *e* need not be located at the ends of the slots but may be a little above or at the side of the slots, as will clearly appear when their purpose is described below. The notches *b* 80 and the horizontal rows 0, 1, 2... of the cards correspond to or are located opposite to one another. The number of horizontal rows, provided on the shown card, is ten, which number is the most suitable for 85 numeral data, made according to the decimal system (another number of rows may, however, be used). For the designating of a number consisting of three figures, three sections are then necessary. In the first 90 section a slot corresponding to the centenary figure is made, in the second section a slot corresponding to the decade figure is made and in the third section a slot corresponding to the unit is provided. The manner in which cards arranged as shown in 95 Figs. 8 and 9 and provided with slots as shown in Fig. 9 and described above may be sorted in accordance with the different confessions of faith, civil status and so on of 100 the corresponding persons will be described below, after the apparatus adapted for effecting the sorting operation has been described.

The sorting apparatus consists of a rectangular frame, Figs. 1 and 2. The longitudinal sides of the said frame consist of bars 1, in which vertical recesses 2 of uniform depth are provided. The number of recesses 2 is the same as the number of 1 vertical sections 1, 2... of the cards and they are located at the same distance from one another as the said sections. The recesses of the one bar are located opposite to the recesses of the other bar. In the inner 1 sides of the end pieces 3, at each corner of the frame, angle-pieces 4 of metal or the like are fixed, which are flush with the inner sides of the frame and extend upward along the end pieces 3 of the frame. The said 1 pieces 4 and the end pieces 3 guide the cards, as they are mounted in the frame, as stated below. In order to render the frame sufficiently stable, the said end pieces 3 besides are connected by means of two longitudinal 1

rods 5, one only being shown in Fig. 1. The top part of one of the end pieces of the frame, which together with the top parts of the corresponding angle pieces are designated with 3¹, 4¹, is movable inward and outward, as shown in Figs. 3 and 4. The said top part 3¹, 4¹ is called "adjusting block" in the following description. The object of the said adjusting block is to bring the cards, mounted in the frame, into a position in which their ends are flush with one another. The said adjusting block is guided by the top edges of the bars 1, which are bent inward partially as shown in Fig. 4.

For the moving of the block inward and outward the apparatus is provided with a shaft 7, which is journaled in the bars 1 and provided with two eccentrics 6 and may be rotated by means of a button 8, fixed to one of its ends, Fig. 2. The said eccentrics 6 are embraced by the adjusting block, as shown most clearly in Fig. 3. The sorting apparatus is provided with a device which locks by groups the cards mounted in the frame. The said device, shown in detail in Figs. 5 and 6, consists of rods 9, sliding in one of the end pieces of the frame and located one above another. To the inner ends of the said rods 9 triangular ribs 10 are fixed, which extend longitudinally of the end piece of the frame. The number of rods with ribs 10 is equal to the number of notches b of the cards and the distance between the ribs 10 is equal to the distance between the said notches. In the hollow end piece of the frame spiral springs 11 are located, which surround the rods 9 respectively and the one end of which is fixed to the rods, while the other end of the same is fixed to the end piece of the frame in such manner that the springs tend to pull the rods inward i. e. to move the ribs 10 toward the cards mounted in the frame. The said ribs 10 are guided by pins 12, sliding in the end piece 3 of the frame. The rods 9 with the ribs 10 are held in the inactive position, shown in Fig. 5 by full lines, by catches 13, pivoted to the end piece and forced down by springs 14 into notches provided in the rods 9. For the disengaging of the catches 13 a swingable arm 15 is provided, from which a link 16 extends upward. The said link 16 is provided with slots 17, engaged by pins 18 fixed to the catches 13 respectively.

To the apparatus a bar 19 belongs, shown in detail in Fig. 7. The said bar 19 is provided at its ends with springy hooks 20. The bar 19 is adapted to be mounted into the recesses 2 of the bars 1. As the bar 19 is located in the said recesses, the hooks 20 engage the bars 1 and lock the bar 19.

When cards, arranged as shown in Fig. 9, are to be sorted, for instance according to the confessions of faith of the persons represented by the cards, consequently in accordance with the slots provided in the section 3 of the cards, the bar 19 is mounted into the third recess of the bars 1 from the left as viewed in Figs. 1 and 2. A collection of cards is then mounted in the sorting apparatus in such manner, that the cards cross the bar 19. The cards are somewhat shorter than the distance between the end pieces 3 of the frame, so that the cards easily descend in the frame, the cards being, besides, so arranged that the slots c provided in the vertical sections 3 are located right above the bar 19. If the cards are then released and, if necessary, are slightly shaken, they will sink down into the frame, guided by the end pieces of the same. The cards will then straddle the bar 19 by their slots c. Consequently, the cards sink to different levels in the frame according to the length of the slots c, so that cards, representing persons of the Lutheran confession, are all located at the same level in the frame, while cards, representing persons of the Catholic confession are located at another level, which is the same for all the latter cards. In Figs. 1 and 7 cards are shown, located at different levels. In order that the cards may easily sink down on the bar 19 wedge-shaped notches f are provided at the lower ends of the sections, as shown in Fig. 8. The width of the slots of the cards is somewhat greater than the width of the bar 19. When all the cards have been brought into their proper positions on the bar 19, the openings e, located at the ends of the slots embracing the bar 19, form a channel extending through the card collection, so that, by looking through the said channel, one can ascertain, if all cards are in their proper position. If any card or cards are not in the proper position i. e. have not perfectly sunk down onto the bar 19 with their slots, the said channel is closed, so that one can not look through the same.

For enabling the locking device to operate all cards located in the frame must be flush with one another. This is effected by moving the adjusting block 3¹, 4¹ inward by rotating the shaft 7 through one half of a revolution, the eccentrics being thus brought into a position, in which they lock the block. When all the cards have thus been brought into the proper position, the arm 15 is raised, so that the catches 13 are disengaged from the rods 9 and the latter together with the ribs 10 are moved inward by the springs 11. The edges of the cards, which are provided with the notches b, face the locking device, so that the ribs 10 engage the said notches and lock the cards. A fork, not shown, is then threaded into the holes a of the cards of the uppermost group, which is then released by withdrawing the uppermost rod 9. All cards of the said group may then be pulled upward by means

of the fork, consequently, in the present case, all cards representing persons of the same confession of faith, for instance the Lutheran confession. The next group of 5 cards is then released and, withdrawn in the same manner, cards being thus received representing persons of another confession of faith, for instance the Catholic confession and so on. Consequently, all the cards 10 are sorted in respect of different confessions of faith. In the same manner the cards are sorted in respect of the civil status, the bar 19 being then mounted in the fourth recess of the bars 1 and the cards threaded on the 15 bar 19 with the slots provided in the section 4.

The invention may, evidently, be modified in many respects without exceeding the limits of the same. Thus, for instance, the 20 slots may extend from points located at a distance from the lower edge of the cards, as shown in Fig. 12. The lower ends of all the slots made in the same vertical section of the cards must, however, be located 25 at the same distance from the lower edge of the cards. In this case a stick for instance may be used instead of the bar 19, which stick is threaded into the slots and is then mounted into the corresponding 30 recesses 2 of the bars 1. After the cards have descended to their proper position and have been locked, the stick is removed and the cards withdrawn by groups in the same manner as stated above.

35 The vertical sections 1, 2 . . . Fig. 8, in which slots are provided, must not be marked on the cards. By means of a special apparatus for cutting the slots, they may, nevertheless, be easily provided in 40 their proper position. Instead of the notches *b*, Fig. 8, for the locking of the cards, holes *g* may be provided in the cards, as shown in Fig. 10. For the locking of the cards needles or sticks are then used which are 45 threaded into holes provided in the sorting frame and the holes of the cards and are withdrawn in their proper turns. The function of the holes *g* may be fulfilled by a wire *h*, Fig. 11, bent into loops and fixed 50 in the card. One or more wire loops may be fixed to the top part of the cards and substitute for the openings *a*, Fig. 8. A notch provided in the top part of each end edge of the cards may be used for the same 55 purpose. The cards may be provided with one or more rows of holes, loops or the like, which rows extend from the bottom edge of the cards to the top edge of the same and are parallel to the sections, 60 adapted for the slots, the lower holes, etc., being used for the locking of the cards, and the upper holes being used for the withdrawing of the same, so that a plurality of groups may be withdrawn simultaneously. 65 Fig. 13 shows a card, which is provided at

its top edge with a flap *i*, in which a hole *k* is made. Such a flap with a hole may be provided also at the opposite edge of the card. The said flaps with holes may be used partly for the locking of the cards 70 partly for the withdrawing of the cards from the collection.

Locking devices as well as adjusting blocks may, evidently, be provided at both ends of the frame. In Fig. 14, which shows 75 parts of a sorting apparatus, adjusting blocks are provided at both ends of the frame of the apparatus. The end pieces are denoted by 3^a, their top parts by 3^{a'} and the top parts of their corresponding angle 80 pieces by 4^{a'}. Owing to the fact, that the cards, supported by the bar 19 or its equivalent, will slant toward its one end or the other, the guides of the adjusting blocks preferably have an oblique position, as 85 shown in Fig. 14, so that the adjusting block, when moved inward for adjusting the cards, swings the ends of the same somewhat upward and forces the cards into a horizontal position. The adjusting operation is effected by means of the block 90 which is located farthest from the bar 19, mounted in the frame of the apparatus, and toward which, consequently, the cards slant.

Having now described my invention, what 95 I claim as new and desire to secure by Letters Patent is:

1. Cards for statistic or similar purposes having one or more sections on the cards provided with slots of different length, 100 which slots extend from one end of the sections respectively, one slot of a certain length and provided in a certain section designating a certain group of a classification corresponding to the section, substantially as described and for the purpose set forth.

2. In cards for statistic or similar purposes means for locking the cards by groups in a sorting apparatus, so that the cards of 110 a free group can be withdrawn, without the other cards accompanying the same, and one or more sections on the said cards provided with slots of different length, which slots extend from one end of the sections respectively, one slot of a certain length and provided in a certain section designating a certain group of a classification corresponding to the section, substantially as described and for the purpose set forth.

3. In cards for statistic or similar purposes means for locking the cards by groups in a sorting apparatus, so that the cards of a free group can be withdrawn, without the other cards accompanying the same, and one or more sections on the said cards provided with slots of different length, which slots extend from one end of the sections respectively, one slot of a certain length and provided in a certain section designating a 130

certain group of a classification corresponding to the section, and means for the connecting with the cards of an implement adapted for the withdrawing of the cards 5 from the collection, substantially as described.

4. In an apparatus for sorting cards for statistic or similar purposes, means for locking the cards by groups in the sorting apparatus, so that the cards of a free group can be withdrawn, without the other cards accompanying the same, and cards having one or more sections on the same provided with slots of different length, which slots extend 10 from one end of the sections respectively, one slot of a certain length and provided in a certain section designating a certain group of a classification corresponding to the section, and means for the connecting with the 15 cards of an implement adapted for the withdrawing of the cards from the collection, substantially as described.

5. Cards for statistic or similar purposes, having one or more sections on the said cards 25 provided with slots of different length, which slots extend from one end of the sections respectively, one slot of a certain length and provided in a certain section designating a certain group of a classification 30 corresponding to the section, and said cards having an opening for each slot, which openings have the same position with relation to the inner ends of the slots, substantially as described and for the purpose set 35 forth.

6. In an apparatus for sorting cards for statistic or similar purposes provided with one or more sections with slots of different length and extending from one end of the 40 sections respectively, one slot of a certain length and provided in a certain section designating a certain group of a classification corresponding to the section, the combination of a frame, in which the cards are 45 mounted, and a bar adapted to be mounted in different places in the said frame, corre-

sponding to the sections of the cards, and to be straddled by the cards with the said slots, substantially as described and for the purpose set forth.

50

7. In an apparatus for sorting cards for statistic or similar purposes provided with one or more sections with slots of different length and extending from one end of the sections respectively, one slot of a certain length and provided in a certain section 55 designating a certain group of a classification corresponding to the section, the combination of a frame, in which the cards are mounted, a bar adapted to be mounted in different places in the said frame, corresponding to the sections of the cards, and to be straddled by the cards with the said slots, a piece provided at one end or both ends of the frame, guides for the said pieces 60 and means for moving the pieces against the cards, located in the frame, for adjusting the same.

65

8. In an apparatus for sorting cards for statistic or similar purposes provided with notches in one of its end edges or both its end edges, the combination of ribs slidably mounted in the frame of the apparatus, and means for bringing the ribs into engagement with the said notches for locking by groups 75 the cards mounted in the said frame, substantially as described and for the purpose set forth.

70

9. In an apparatus for sorting cards for statistic or similar purposes provided with notches in one of its end edges or both its end edges, the combination of ribs slidably mounted in the frame of the apparatus, springs tending to bring the said ribs into engagement with the said notches, catches, 85 holding the ribs in inactive position, and means for disengaging the said catches simultaneously, substantially as described and for the purpose set forth.

80

In witness whereof, I have hereunto signed 90 my name.

KARL EMIL LEONARD LIEDSTRAND
